AUSTIN LE BOUTILLIER, OF BALTIMORE, MARYLAND, ASSIGNOR TO WESTERN ELECTRIC COMPANY, INCORPORATED, OF NEW YORK, N. Y., A CORPORATION OF NEW YORK

APPARATUS FOR CLEANING AND TENSIONING MATERIAL

Application filed March 12, 1931. Serial No. 521,996.

This invention relates to apparatus for cleaning and tensioning material, and more particularly to apparatus for cleaning and tensioning wire, ribbon or other elongated material.

It is desirable, in some instances, to clean wires or other materials before performing certain operations thereon, and to tension the materials while performing such operations. For example, in the manufacture of rubber insulated wires, it is not only desirable to clean the wires before applying the rubber insulating material thereto, but it is also important that the wires be properly tensioned during the application of the covering material. Furthermore, when applying a common insulating covering to two or more wires, it is necessary that the wires be maintained under equal tension.

An object of the present invention is to provide a simple and efficient apparatus for cleaning and tensioning material.

One embodiment of the invention contemplates the provision of apparatus for cleaning and tensioning a pair of wires being advanced to a wire insulating machine, wherein the wires are passed on opposite sides of two wiping members of leather or similar material spaced along the wires and carried on a pivoted self-centering member, each wire also being engaged by an opposing pair of similar wiping members spaced from the first wiping members and carried upon pivoted spring pressed members, whereby the pressure of the wiping members upon the wires is equalized and the wires are thus maintained under equal tension.

It is believed that a complete understanding of the invention will be had from the following detailed description when read in conjunction with the accompanying drawing, wherein

Fig. 1 is an elevational view of a wire cleaning and tensioning apparatus embodying the features of the invention;

Fig. 2 is a plan section on line 2-2 of Fig. 1, and

Fig. 3 is a vertical section on line 3-3 of Fig. 2.

Referring now to the drawing, wherein

like reference characters designate the same parts in the several views, the numeral 10 indicates a portion of a vertical supporting standard upon which a support illustrated in the form of a horizontal plate 11 is pivotally supported intermediate its ends, as at 12. A supporting member illustrated in the form of a yoke 14 is pivoted at 15 to one end of the plate 11, and carried at the opposite end of the plate is a pair of spaced wiping and tensioning members 16-16 consisting of strips of leather or other suitable material. The members 16 extend through spaced rectangular slots in the plate 11 and are secured therein by removable wedge shaped pins 17-17, whereby they are vertically adjustable with respect to the plate.

Secured at one end to opposite sides of the pivoted yoke 14 is a pair of leaf springs 18-18 which extend along and are spaced from opposite sides of the pivoted plate 11. Each of these leaf springs is formed with spaced jaws 19-19 for receiving and yieldably clamping therein a pair of wiping and tensioning members 20-20 similar to the members 16. The jaws 19 are constructed so as to permit vertical adjustment of wiping members 20 with respect to the supporting springs 18 in the same manner as members 16-16; that is, by removable wedge-shaped pins similar to pins 17-17. It will be observed that wiping members 20 are offset or staggered with respect to wiping members 16 and that the pivoted plate 11 is notched as at 22, to permit the movement of wiping members 20 toward wiping members 16 under the tension of springs 18.

The operation of the above described apparatus is as follows: A pair of wires 25-25 drawn from a supply source (not shown) pass along opposite sides of wiping members 16 and between wiping members 16 and 20 before they are delivered to the insulating machine (not shown). Each two opposed wiping members 20 are associated with a particular wiping member 16 as a coacting triad operating on both wires 25. The two members of each of the three possible pairs in such a triad have relative movability of position under the pressure of

the springs 18. It is obvious that the wires are not only cleaned but also tensioned by the frictional drag exerted thereon by wiping members 16 and 20, due to the tension 5 of the supporting springs 18. The pressure and hence the frictional drag exerted by the wiping members upon the two wires is equalized, due to the pivotal connection 10 of the supporting yoke 14 and the pivotal connection 12 of the supporting plate 11, and therefore, the two wires are constantly maintained under equal tension. When desired, the wiping members may readily be adjusted with respect to their supports to present 15 a new wiping surface to the wires.

It is to be understood that the invention is not limited to the specific embodiment thereof herein illustrated and described, except insofar as is defined by the appended 20 claims.

What is claimed is:

1. In an apparatus for cleaning and tensioning wires, a rigid vertical supporting standard, a supporting plate pivotally supported intermediate its ends on the vertical supporting standard, a wire engaging member carried at one end thereof, a supporting yoke pivoted at the opposite end thereof, and means carried by the yoke for supporting 25 a pair of spaced wire engaging members and for yieldably urging said members toward the first mentioned member.
2. In an apparatus for cleaning and tensioning wires, a rigid vertical supporting standard, a supporting plate pivotally supported intermediate its ends on the vertical supporting standard, a wiping member carried at one end thereof, a supporting yoke pivoted at the opposite end of said 30 plate, a pair of spaced leaf springs secured to and extending from the supporting yoke, and a wiping member carried by each of the leaf springs and yieldably movable toward the first mentioned wiping member.
3. In an apparatus for cleaning and tensioning wires, a supporting plate pivoted intermediate its ends, a pair of spaced wiping members carried at one end thereof, a supporting yoke pivotally carried at the opposite end thereof, a pair of leaf springs secured to the supporting yoke and extending 35 therefrom along opposite sides of the said wiping members, and a pair of wiping members carried by each of the leaf springs, yieldably movable toward the first mentioned wiping members, and offset with respect thereto.

In witness whereof, I hereunto subscribe my name this 24th day of February A. D., 60 1931.

AUSTIN LE BOUTILLIER.
